UNITED STATES PATENT OFFICE.

JACOB DIDION, OF VALLEY PARK, MISSOURI.

RUNNER BAR FOR PLATE-GLASS-GRINDING MACHINES.

Application filed November 10, 1924. Serial No. 748,832.

My invention relates to improvements in runner bars for plate glass grinding machines and has for its primary object the construction of runners which can be readily attached to and removed from the machine.

A further object is to construct runner bars for plate glass grinding machines in which the runner bars are mounted on plates and secured thereto in such a manner as to be readily removed therefrom for renewing or in the case of a defective runner bar or block, and in which only one screw is necessary to hold a single line of runner bars in attached position.

Heretofore, the runner bars were attached to the disks or runner by means of screws, the deck being of wood, the screw holes would in a short time lose their thread so that a screw would no longer hold therein and the runner bars would have to be shifted and so that the screws could get a new hold, and it quite frequently happened that it was impossible to secure the runner bars without striking some of the old screw holes. This necessitated considerable waste of time in plugging up these holes and after a few changes, the entire deck of the runner or grinding disk became useless and had to be renewed.

In my device, securing strips are fastened to the deck permanently and the runner bars are removably secured thereto, thus the deck of the grinding disk or runner can be used indefinitely as the securing strips do not have to be removed when renewing worn out runner bars or replacing defective ones.

In the drawings:—

Fig. 1 is a top plan view of a grinding machine such as used for plate glass, with parts broken away;

Fig. 2 is a side elevation of the same;

Fig. 3 is a top plan view of the runner bar supports showing the manner of interlocking the ends thereof;

Fig. 4 is a similar view with the runner bars in position;

Fig. 5 is a side elevation of Fig. 4;

Fig. 6 is an enlarged longitudinal vertical section of a runner bar support showing the manner of filling in the spaces between adjacent runner bars;

Fig. 7 is a similar view taken of the locking end of the runner bar support and showing the manner of preventing the runner bars from shifting and becoming loosened;

Fig. 8 is an enlarged vertical cross section taken on the line 8—8 of Fig. 4;

Fig. 9 is an enlarged top plan view of a portion of one of the runner bars with parts broken away;

Fig. 10 is an enlarged perspective view of one of the filler plates;

Fig. 11 is an enlarged perspective view of the locking plate;

Fig. 12 is a bottom plan view of a portion 65 of one of the grinding disks or runners with several rows of runner bars thereon showing the manner of staggering the runner bars, and also the method of inserting the runner bars in position; and

Fig. 13 is a fragmental bottom plan view 70 of a modified form of grinding disk or runner showing the runner bar securing means formed integral therewith.

In the construction of my device I employ 75 an ordinary plate glass grinding machine comprising a table 13 which is mounted on truck wheels 14, these wheels ride on tracks so that the table can be moved from place to place.

In the floor of the factory is provided a pit 15 in which is located a platform 16, this platform is provided with tracks so that the table 13 can be moved thereon. Projecting through the platform is a support 17 85 which extends above the floor of the factory, but of such a height that the table may pass freely thereover. The platform 16 is so arranged that it can be raised and lowered, the purpose of this will be explained in detail later.

The underside of the table 13 is provided with gear teeth 18 which design to mesh with a bevel gear 19 which is driven by means of a pulley or other power device 20. 95 Located on opposite sides of the pit 15 are standards 21 which are connected at their upper ends by means of a cross bar 22 and through which shafts 23 pass. These shafts are mounted in bearings 24 and are free to 100 rotate therein and also to move up and down. The shafts 23 are also provided with collars 25 which are spaced apart and which are secured to the shaft. Between these collars is loosely mounted on the shaft a block 105 26 which has pins 27 projecting from opposite sides thereof. These pins extend through slots 28 formed in the bifurcation 29 of the lever 30. The lever 30 is pivotally mounted intermediate its ends in the stand- 110

ard 21, as at 31, its free end extending some distance beyond these uprights or standards and has attached thereto means by which the lever can be raised and lowered. This is 5 preferably done by means of a hydraulic cylinder, although other mechanism may be used. This part, however, is not shown as it forms no part of my invention and there are numerous devices on the market used at 10 the present time for this purpose.

Detachably secured to the lower end of the shaft 23 by means of a key 32 is a collar 33, to the underside of which is secured a grinding disk or runner 34. Arranged in parallel rows across the face of the disk are runner bar supports 35, one end of which is provided with a dove-tailed tongue 36, the other end with a dove-tailed groove 37 by means of which the runner bar supports may 15 be interlocked. The runner bar supports are provided with a plurality of pads or blocks 38, and intermediate these pads or blocks are depressions 39 leaving ribs 40 along each edge of the runner bar support, which ribs 20 are located between the pads 38.

Extending upward from the pads are bosses or lugs 41, the inner edge of these lugs is dove-tailed or undercut as at 42 (see Fig. 8). The projections 41 or rather the undercut 30 portion is also arranged at an angle to the longitudinal axis of the bar so that the space between the points 43 is narrower than the space between the points 44, this is to 35 permit the runner bars to be wedged into position and held against accidentally coming out.

One of the runner bar supports of each set is provided with a plain end 45, that is, it 40 has no dove-tailed tongue or groove, and is so arranged that the depression 46, which is at the end of that bar, is closed by means of the rib 47. This is for the purpose of holding the locking plate 48 in position and to 45 take off all end thrust from the screw 49 which passes through the plate and into the screw threaded opening 50 formed in the depression 46. The manner of locating this block is clearly shown in Fig. 7.

The runner bars consist of a strip 51 which 50 is provided at spaced apart intervals with substantially rectangular projections or blocks 52, these projections are relatively thick and with them the grinding of the glass is done.

Projecting outward from the strip 51 and 55 located at opposite sides of the projection or block 52 are wings 53 which have their outer sides inclined both vertically and longitudinally so as to fit snugly between the projections 41. Extending across the strip 51 and adjacent the bosses 52 are breaking grooves or slots 54, these are for the purpose of 60 permitting the strip to be broken at that point when it is necessary to remove one of the blocks for any purpose.

Between adjacent ends of the runner bars are placed filler plates 55 which are provided along their bottom edges with lips 56, these lips are designed to pass underneath the ends of the strips 51 and prevent the plate from 70 falling out, side movement of the strips being prevented by means of the ribs 40. The manner of inserting these plates will be explained in detail later.

The locking plate 48 is provided with an 75 opening 58 through which the screw 49 passes, and with only one lip 59, the opposite side 60 of the block being straight so as to abut the rib 47. The filler plates 55 may be made of various widths, as sometimes one of the runner bars will fit farther into the space between the projections 41 and thus make the space between adjacent ends of the bars less; at other times it may not fit in so far thus widening the space. The locking plate 80 48 can also be made in various widths for the same purpose.

The runner bar supports are provided at intervals with openings 61 which are formed through the ribs 40 and are for the purpose of permitting screws to pass therethrough so that the supports may be attached to the grinding disk or runner 34.

In attaching my improvement to the grinding disk, the table 13 is first run under the 95 disks 34, the disks lowered on the surface of the table and the key 32 driven out. The lever 30 is then moved so as to raise the shaft 23 out of the collar 33 and the table then 100 pushed away bearing with it the grinding disk or runner 34. At a convenient point the disk 34 is removed from the table and inverted and the runner bar supports secured to its face. These runner bar supports are 105 arranged parallel to each other and spaced apart. The arrangement preferably being such that when the runner bars are in position the blocks thereof will be staggered (see Fig. 12).

In placing the runner bars in position I 110 start from the end opposite the end 45 and place a runner bar in the position shown at the extreme right in Fig. 12. This bar is then forced forward until the wings 53 have engaged securely with the undercut edges 42 of the projections 41 thus wedging the bar in place. A filler block is then inserted in position, abutting the end of the bar just secured and with one of the lips under said bar and the next bar placed in position in the same manner, its end passing over the remaining lip. This is continued until the entire runner bar support is filled, the last thing put in position, being the locking plate 48. In this manner all of the rows 115 of runner bar supports are filled, it, of course, being understood that the runner bar supports gradually decrease in total length as they work out from the center of the runner. The device is then ready to be 120 125 130

taken back to the grinding machine, it is again inverted and placed on the table with the runner bars resting thereon, moved back to the machine and secured to the shaft 23. 5 After which the shaft is elevated so as to raise the grinding or runner disk above the table, the table is now moved to a convenient point where sheets of plate glass are attached thereto in the manner well known to the 10 art. After which the table is again brought underneath the machine and rests on the platform 16, this platform is then lowered until the table comes to rest on the support 17. This support being so arranged that 15 the table will rest securely thereon and be permitted to rotate. The platform 16 is then lowered away from beneath the wheels 14. This placing the table on the support also causes the gears 18 and 19 to engage so 20 that when the pulley 20 is rotated the table will turn. Suitable abrasive material is then placed on the glass and the grinding disk or runner 34 lowered until the desired pressure on the glass has been reached.

25 The table is then rotated and due to the friction between the glass and the runner bars the disks 34 also rotate causing the runner bars to rub over the surface of the glass and together with the abrasive material, grind it. Should it occur that one of 30 the blocks of a runner bar has a flaw in it, such as a sand or blow hole, or other defect which renders it useless, this block may be readily removed by removing the locking 35 plate 48 and longitudinally sliding each runner bar from its operative position between the spaced lugs 41 removing the bar and breaking it along the grooves 54 so 40 that it is not necessary to destroy the entire runner bar, a single runner block may then be inserted in its place, it being necessary, of course, to insert a filler plate at each end of this runner block so as to hold it in position. The runner bars can also be readily 45 detached when worn out, by merely removing the lock plate 48 and driving the runner bars toward the end 45. In other words, the removing of the runner bars is the exact reverse of placing them in position. The 50 runner bar supports are made in interlocking sections to take care of the varying lengths of runner bars which is occasioned by placing them parallel to each other across the face of the disk.

55 In Fig. 13 I have shown a modified form of construction in which the ribs 62 are formed integral with the grinding disk or runner 63, and in which the recesses 64 are also formed in the face of the disk. The 60 ribs 62 are undercut in the same manner as the ribs or projections 61 of the runner bars previously described.

65 It will also be noted from this figure that these ribs are so arranged as to cause the runner bars to be staggered. The recesses

64 serve the same purpose as the recesses 39 and the locking means is also the same. This last construction is used where a metal grinding disk is employed instead of a wooden decked disk.

70 The breaking groove 54 formed in the runner bars adjacent the blocks permit the blocks to be separated from each other readily and will not destroy the broken off block or the remainder of the runner bar, 75 as is the case at the present time. In the runner bars now in use screw holes are formed through the portion of the runner bar between the blocks, these screw holes are arranged diagonally to each other and 80 when a bar breaks, it invariably breaks through the two holes and the breaks are diagonal. It is then necessary to cut off the two blocks adjacent this diagonal break in order to preserve the screw holes adjacent the remaining blocks. In my device, 85 with the grooves as illustrated, the break will be straight across and since no screws are employed for holding the runner bars to the disk, it is not necessary to discard 90 any of the blocks. Furthermore, by having my runner bars quickly detachable, a grinding disk can be readily equipped with a new set of runner bars in a relatively short time, 95 approximately between two and four hours whereas formerly, or with the present style now in use, it required several days to renew the runner bars besides which, the old type quickly wears out the grinding disk deck because of the necessity of using screws 100 to hold the runner bars in place.

Having fully described my invention, what I claim is:—

1. A device of the class described comprising a disk, a plurality of runner bar supports, each of which is provided with a series of spaced apart dove-tailed, wedge-shaped recesses located above one face of said bar, means for securing said runner bar supports to said disk, a plurality of runner bars, each of which is provided with a series of spaced apart projections, a wing formed integral with each side of said runner bars and located adjacent to and opposite each projection, the length of said wings being less than the distance between the adjacent dove-tailed, wedge-shaped recesses whereby said runner bar can be placed in position on or removed from said runner bar support without moving the same the full length of 110 the runner bar support, and a locking plate located in the runner bar support for holding the runner bar in position.

2. A device of the class described comprising a disk, a plurality of runner bars, a plurality of longitudinally spaced wings extending laterally from each side from each of said runner bars, laterally and longitudinally spaced apart means secured to the face of said disk, the longitudinal spacing of 125

which is greater than the length of the wings carried by the runner bars whereby said runner bars may be secured to said disk by inserting the wings between the spaced 5 apart means and effecting by a relatively short longitudinal movement to seat the wings in the spaced apart means, and may be removed by the inverse process, and means located at one end of said runner 10 bars for locking the same in position.

3. A device of the class described comprising a disk, a plurality of runner bar supports extending across the under face of said disk in parallel relation to each other, longitudinally spaced projections integral with the side of each of said runner bar supports extending from the face thereof, said projections forming dove-tailed, wedge-shaped recesses, a plurality of runner bars having 15 dove-tailed, wedge-shaped longitudinally spaced apart wings projecting from each side thereof, said wings being of less length than the longitudinal space between adjacent projections on said runner bar supports and adapted to engage with the projections on the supports for securing the 20 bars thereto whereby a runner bar can be attached to and removed from said support without moving the same the full length of

said support, and means located adjacent 30 one end of said bars for preventing longitudinal movement thereof whereby accidental disengagement of the wings from the projections is prevented.

4. A device of the class described comprising a disk, a plurality of runner bar supports provided with projections laterally opposite each other and longitudinally spaced apart forming dove-tailed, wedge-shaped recesses, means formed on the end 35 of said runner bar supports for interlocking the same together, runner bars provided on their edges with outwardly extending longitudinally spaced apart wings of less length than the longitudinal space between said 40 projections whereby a runner bar may be placed in position and the wings forced into the recesses without moving the runner bar the full length of the support, and means located at the end of one of said runner 45 bars for preventing the runner bars from moving longitudinally whereby the same are prevented from becoming accidentally disengaged.

In testimony whereof, I have signed my 50 name to this specification.

JACOB DIDION.
